and Joseph M. Kovarik, Jr., Chicago, Ill., as-
signors to Crane Co., Chicago, Ill., a corpora-
tion of Illinois

Application February 26, 1937, Serial No. 127,832

6 Claims. (Cl. 251—20)

While applicable to ordinary valve structures, our improvements embody particular advantages in bath supply valves and the like wherein frequent valve operation occurs and also in which it is frequently necessary to replace valve seats or closures principally because of abuse, as for example, the failure to close the valve properly, or because of abnormal wear due to excessive frequency of operation.

10 An important object of the invention lies in the provision that the actuating member may also serve equally well in the capacity of an escutcheon or protective cover for the operating parts. This construction lends itself to an economical installation, permitting greater ease of cleansibility with exceptional compactness resulting from the omission of the usual separate and protruding valve operating means.

One of the important objects of the invention 20 lies in the fact that all of the operating parts are constructed and assembled in such a manner that no special types of wrenches or tools are required to remove any of the parts either for inspection or repair, and therefore the equipment will be maintained in improved condition with less inconvenience than heretofore.

More specifically, an important advantage lies 30 in the fact that the lower end of the centerpiece is broached or otherwise formed polygonally in order to engage a complementary polygonal shape on the upper end of the renewable seat unit, thereby facilitating easy removal of the latter.

It is a further important object that for concealed bath and shower fixtures which are necessarily mounted within and behind walls, a new and readily expandable construction has been devised which provides for simple adjustment to allow for the many variations which are encountered in the roughing-in dimensions during the course of installation. With more particularity, therefore, an advantage of the construction lies in making the operating stem with an exposed end which is broached for a considerable distance greater than the length of the broaching through the operating handle so that the end of the stem can easily be made to suit the roughing-in dimension required, by the simple expedient of cutting the length of the stem to the desired size. In so doing, the handle can be maintained approximately the same distance from the face of the wall for all reasonably variable installations. By such novel arrangement, obviously, the objectionate provision requiring different lengths or sizes of stems to take care of the varying

dimensions in roughing-in is conveniently overcome.

As hereinafter described, another important advantage lies in the fact that by the substitution of either a single one or a multiplicity of spacing washers the journalling centerpiece may be properly positioned axially so that the lost motion of the operating handle may be accurately adjusted.

Another object lies in the construction of a 10 valve trimming in which objectionable noises, such as squeals and chattering under normal operating conditions, are minimized.

Other objects and advantages of the invention will appear from a reading of the specification which follows in connection with the patent drawing, in which:

Fig. 1 is a central vertical sectional assembly of a preferred embodiment of the valve and its operating mechanism.

Fig. 2 is a transverse section taken on the line 2—2 of Fig. 1, illustrating a preferred form of non-rotatable relation between the centerpiece and the sleeve.

Referring to Fig. 1 of the drawing, the number 1 designates the casing or valve body which is provided with the conventional inlet 2 or 3 or both, as the installation may require, and with the side outlet 1b. Centrally positioned within the casing 1 and dividing the latter into chambers separating the inlet from the outlet, a dividing wall or diaphragm 1a has its transverse wall apertured for the threaded seat opening 4 into which the sleeve 5 is threadedly retained. The lower portion of the said sleeve 5 is provided with the seat 6 against which the disc or closure 7 abuts when in seated relation thereto, and, as indicated at 5a, the sleeve is counterbored slightly larger than the bore or seat opening 20, in reducing objectionable flow 30 noises, and a similar result is accomplished in making the face of the disc 7 flush with the outer edge of the retainer ring 11, as indicated at 11a. Further, and also for this purpose, the disc 7 is recessed as at 7a to receive the shoulder 40 of the lower stem 8. The disc 7 is removably connected in the usual manner to the winged lower stem 8 by means of the threaded extension 9, the retainer ring 11 and the threaded nut 12. Below the winged guide, as indicated at 8a, the 50 lower stem diameter is substantially reduced so as to provide an adequate flow space as at 20, and thereby also minimizing water-flow noises. The lower stem 8 is preferably integrally provided with the narrow extending shank 13 hav- 55

ing the enlarged portion 14 terminating in a shoulder 15. The enlarged portion 14 serves to guide the spiral spring 16 while the shoulder 15, as illustrated, serves as a retainer for the spring at one end, while at the other end it is retained by the shoulder 17 of the sleeve 5. Beyond the shoulder 15 the shank 13 preferably resumes its narrow diameter, as at 18, terminating in the roughened or knurled end portion 19 fitting within the hollow 21 of the threaded stem or valve actuating means 22. The purpose of the knurled end portion 19 of the lower stem 8 is to provide for removal of the loosened unit by means of pliers and the like when the sleeve 5 is free, as hereinafter described. The upper stem 22 is threadedly journaled within the centerpiece 23 so that by its rotation in one direction or the other, it is either moved toward the valve closure or is moved away from the closure. The centerpiece 23 is held in abutting non-rotatable relation against the annular threaded end of the casing 1 by means of the threads 24. While only a single gasket is shown interposed at the said threaded end 24, several superposed spacing gaskets may be provided at this point for the purpose of maintaining the desired clearance between the upper and lower stems, as indicated at 19 and 21a, and within the recess 21a, so that the said clearance does not permit too much rotational travel of the stem 22 before contacting with the knurled end 19 and thereafter forcing the disc 7 from the casing seat 6.

As shown more clearly in the transverse section of Fig. 2, the sleeve 5 is of polygonal cross-section in its outer contour and is enclosed within in a similar polygonal-shaped recess. Thus, by the rotation of the centerpiece 23, as accomplished by the application of an ordinary wrench to the polygonal-shaped shoulder 26, the sleeve 5 will likewise be rotated. By so doing, the threaded joint at 4 will be broken, thus allowing for the removal, as a unit, of the disc 7, the disc retainer 11, the nut 9, and the winged lower stem 8, together with the sleeve 5. Either the fingers or pliers may be used to grip the knurled end 19 and remove the assembly just described.

In order to maintain the centerpiece 23 in fixed and non-rotatable relation with respect to the upper portion of the casing 1, the threaded bonnet 25, by means of its screw threads which engage the complementary casing threads 24, clamps the shoulder 26 therebetween in the preferably adjustable gasketed joint as previously described, and also serving thereby to confine the packing 28 within its inverted recess 27. An annular hollow plate 29 is held in abutting relation against the wall line 31 by means of the threaded locking ring 32. The actuating upper stem 22 is provided with the extended broached section 33 and with relatively long internal threads 34 for engagement by the capscrew 35 which holds the escutcheon handle 36 which is suitably broached as at 37 to fit non-rotatably upon the said stem broaching 33. Thus it will be evident that by the construction just described the broached end portion of the stem 22 may be conveniently cut off to suit the "roughing-in" variations, and by providing an overhanging or escutcheon type of operating handle 36, there is provided not only an effective operating means, but at the same time it serves as a practical cover to conceal the otherwise exposed parts. It is further evident that the extended lever of the handle 36 may be modified or omitted, as indicated by the dotted lines, un-

der such circumstances, and the operating grip will be simply applied to the periphery thereof.

From the foregoing description it is apparent that the valve of our invention provides for easy renewability or repair of the valve closure member or disc and other internal parts by the comparatively simple expedient of removing first the escutcheon type of handle 36 and then the locking ring 32 which holds the annular plate 29 firmly in position. This is followed by removing the packing bonnet 25 which has its upper portion of such polygonal form as to be readily gripped by the ordinary wrench. The operating stem 22 and the centerpiece 23 may then be removed. By the removal of the threaded packing 25, the centerpiece 23 is then exposed so that the wrench may then be applied so as to rotate the centerpiece 23 in a counter-clockwise direction. Since the lower end of the centerpiece 23 is provided with a polygonal form recess engaging the similarly formed upper end of the sleeve 5, the sleeve 5 is likewise rotated upon its threads 4, and is thus releasable from the casing 1 by lifting out the lower stem 8.

In proceeding to describe the actual operation of our device, assuming the valve to be in the closed position as shown in Fig. 1, it should be noted that the valve is maintained closed with the pressure. Therefore when looking down upon the valve, or in direction indicated by the arrows for the section 2-2, upon rotating the handle 36 the upper stem 22 is rotated upon the internal threads of the centerpiece 23 and the stem is caused to move inwardly so that the end limit 21a of the recess 21 strikes against the knurled end 19 of the shank 18 thereby moving the winged lower stem inwardly in opposition to the action of the spring 16. Thus the disc 7 is displaced from its seat 6 within the sleeve 5, and since the latter is provided with the ports 40, the discharge of the liquid entering through the seat opening 20 within the sleeve 5 continues past the winged guides of the lower stem 8 and into the side outlet 1b.

Upon reversing the direction of rotation of the operating escutcheon handle, the stem is caused to recede and thus allows for the disc to return to its seat under the force exerted by the spring 16 as well as that of the line pressure. Thus we have accomplished a relatively quiet valve for the purpose, capable of being easily suited to variations in installation and capable of repair with minimum of inconvenience and possessing ease of operation.

It is obvious that a detailed construction describing a preferred embodiment of our invention has been illustrated, and that numerous modifications may be made within its scope. We desire therefore to be limited only by the appended claims.

We claim:

1. In a valve of the character described, comprising a casing having respective inlet and outlet openings, a flat seated valve closure member therefor, the said outlet openings being laterally positioned relative to the said closure member, wing-guided actuating means for the said closure member positioned between the said inlet and the said laterally positioned outlet openings, the said actuating means having respective reduced portions above and below the said wing-guided means for the said closure member, a seat for the said closure member, the said seat being slightly flared immediately adjacent to the contact face of the said closure member.

2. A valve comprising a casing having respective inlet and outlet openings, a ported sleeve member within said casing positioned between said inlet and outlet openings, transverse outlet openings within the said sleeve, a valve closure member therefor, actuating means for the said closure member, the said actuating means comprising a stem having a winged guide means interposed between the said inlet opening and the 5 said transverse outlet openings, reduced portions upon the said stem above and below the said guide means and positioned between the said inlet and the said transverse outlet openings of the said sleeve, the said sleeve member having 10 a relieved diametral portion adjacent the said transverse outlet openings within the said sleeve.
3. A valve comprising a casing having respective inlet and outlet openings, a sleeve therebetween within said casing, a valve closure member 15 therefor wholly supported by the said sleeve, the said sleeve having a valve seat inlet opening and transversely positioned port openings communicating respectively with the said casing inlet and outlet openings, actuating means for the said closure member, the said actuating means having reduced portions contained within the sleeve and positioned between the said transversely positioned port openings of the sleeve and within the paths of line flow adjacent to the contact of 20 the closure member with the sleeve seat inlet, the said sleeve having an enlarged diametral portion adjacent the said transversely positioned port openings, a seat for the said closure member, the said seat being rounded on both its inner and 25 outer peripheries.
4. In a valve of the character described, comprising a casing having respective inlet and outlet openings, a plane faced valve closure member therefor, a sleeve within said casing with a substantially thickened and ported portion forming 30 transversely extending passages therethrough, a retaining holder for the said closure member, fluted actuating and guide means for the said closure member positioned between the said inlet 35 and the said ported sleeve portion, the said actuating means having a reduced connection with the said closure member above and below the said guide means, the said latter member having its seating surface flush with the outer peripheral edge of the said retaining holder.
5. A valve comprising a casing having respective inlet and outlet openings, a sleeve within said casing positioned between said inlet and outlet openings, the said sleeve being provided 10 with transversely extending apertures, a valve closure member therefor, actuating means for the said closure member, the said actuating means comprising a stem contained within said sleeve and having a fluted portion interposed between 15 the said inlet opening and said transversely extending apertures, the said stem having reduced diametral sections above and below the said fluted portion, the said sleeve being provided on its exterior with a seat for the said closure member, the said seat having an enlarged inner periphery immediately adjacent to its contact surface for the said closure member, one of said reduced diametral sections of the stem being normally opposite the said transversely extending 20 apertures of the said sleeve.
6. A valve comprising a casing having respective inlet and outlet openings, a ported sleeve therebetween within said casing, a valve closure member therefor, actuating means for the said 25 closure member, the said actuating means having reduced portions positioned within the said sleeve between the said inlet and outlet openings thereof and adjacent to the contact of the closure member with the inlet opening of the sleeve, the said actuating means having a fluted guide portion between the inlet and the ports of the said sleeve, the latter member having a relieved 30 diametral portion surrounding one of said reduced portions of the said actuating means.
